CLAIM

The ornamental design for an adjustable luminaire, as shown and described.

DESCRIPTION

FIG. 1 is a top perspective view of an adjustable luminaire showing my new design.

FIG. 2 is a top view thereof;

FIG. 3 is a bottom view thereof;

FIG. 4 is a front view thereof;

FIG. 4A is an enlarged fragmentary view of the portion identified in FIG. 4;

FIG. 5 is a rear view of the adjustable luminaire shown in FIG. 1;

FIG. 6 is a right-side view thereof;

FIG. 7 is a left-side view thereof;

FIG. 8 is a bottom view thereof in a half-open position; and,

FIG. 9 is a bottom view thereof in an open position.

The portions of the luminaire shown in broken lines form no part of the design.

1 Claim, 6 Drawing Sheets
